UNITED STATES PATENT OFFICE.

FRANK BILLINGS AND ROBERT P. GREENLEAF, OF CLEVELAND, OHIO; SAID GREENLEAF ASSIGNOR TO SAID BILLINGS.

LOADING MACHINE.

1,420,681.

Specification of Letters Patent. Patented June 27, 1922.

Application filed February 25, 1918. Serial No. 218,929.

To all whom it may concern:

Be it known that we, FRANK BILLINGS and ROBERT P. GREENLEAF, citizens of the United States, and residents, respectively, of Cleveland, in the county of Cuyahoga and State of Ohio, and Cleveland, in the county of Cuyahoga and State of Ohio, have invented a certain new and useful Improvement in Loading Machines, of which the following is a full, clear, and exact description.

This invention relates to loading machines and has particular reference to loading machines for use in mines to pick up loosened material such as ore and coal, and deposit the same in cars or other suitable receptacles.

The principal object of this invention is to enable the digging and conveying mechanism, that is to say, the mechanism which receives and conveys the material from in front of the machine to be fed or moved forwardly without the necessity of laying or advancing the track during the period of loading. Further the invention aims to provide a construction such that as this mechanism is advanced, the car or receiving element may be corresponding advanced without moving the supporting part resting on or secured to the rails of the track.

In carrying out the present invention we provide a construction embodying a base or supporting part designed to rest on, or to be secured to the rails of the track, and on this base we provide a second base which may be termed the intermediate base, which is movable forwardly and rearwardly with reference to the lower or sub-base, and which supports the digging and conveying mechanism. Additionally we provide means whereby the car or receiving element may be run up onto the rear end of the sub-base and advanced forwardly along the same as the intermediate base with the digging and conveying mechanism is advanced, so that the car may always be in position to receive the material which is discharged by the conveying mechanism.

The invention may be further briefly summarized as consisting in certain novel details of construction and combinations and arrangements of parts which will be described in the specification and set forth in the appended claims.

In the accompanying sheets of drawings, Fig. 1 is a side view of a loading machine

embodying our invention; Fig. 2 is a top plan view of the same; Fig. 3 is a plan view of the sub-base and the intermediate base which is supported on, and is movable lengthwise of the former; Fig. 4 is a transverse sectional view substantially along the line 4—4 of Fig. 1, looking in the direction indicated by the arrows; and Fig. 5 is a fragmentary section substantially along the line 5—5 of Fig. 1.

The loading machine embodying this invention includes a lower base or sub-base 10 which is designed to rest on, and if desired, to be secured to the rails 11 of a track which may be a mine track. The invention is not necessarily confined in its use to loading material in mines, although it has special utility for that purpose. This sub-base includes a platform 10^a which in this instance is designed to rest directly on the rails 11, and as here shown, is designed to be clamped thereto by clamps 10^b. Any other suitable means of supporting the sub-base on the rails may be utilized, and also for holding the sub-base down to the rails, the clamps 10^b which engage the lower flange of the rails being well adapted for the latter purpose. Additionally this sub-base includes side rails for the upper or intermediate base which supports the digging and conveying mechanism, these rails being here shown in the form of Z-shaped bars 10^c, with lower horizontal flanges 10^d which are bolted or otherwise secured to the platform 10^a, and with outer elevated horizontal flanges 10^e which constitute the tracks for the intermediate base, these flanges 10^e being outside of the track rails 11. Along the inner edges of the horizontal flanges 10^d of the Z-rails 10^c are flanges 10^f constituting rails which are directly above the track rails 11, and form tracks for mine cars as will be explained subsequently.

The upper or intermediate base preferably includes a horizontal frame or platform 12 which as here shown, is about as long as the sub-base, and is supported on the latter in such a way that it can be moved along the sub-base with its forward end projecting well forwardly of the latter. The intermediate base is supported on the sub-base in such a manner that it can be moved easily and at the same time well supported, and to this end the forward portion of the sub-base

2

is provided with rollers 10^g (see Figs. 1 and 5) on which the platform 12 rests, and the rear end of the intermediate base is provided with rollers 12^a and 12^b, the former engaging the upper surface of the flanges 10^e of the Z-rails constituting a part of the sub-base, and the latter rollers 12^b engaging the lower surfaces of these flanges. Preferably the upper rollers 12^a are secured to a cross-shaft 10 12^c at the rear end of the intermediate base so that both rollers may be positively turned, and thus feed the intermediate base forwardly or rearwardly. For this purpose these rollers 12^a are provided with peripheral teeth which engage in suitably spaced openings of the flanges 10^e of the Z-rails 10^e. In effect, the toothed rollers and openings in the flanges of the rails form a rack and pinion construction. The shaft 20 12^c may be turned in any suitable manner such as by applying a crank to one end thereof.

On this intermediate base 12 is mounted any suitable form of digging or receiving 25 and conveying apparatus or mechanism, the function of which is to pick up material at the front of the intermediate base and to convey the same rearwardly preferably at least to the rear of the intermediate base. 30 For convenience we have shown digging and conveying mechanism similar to that constituting the subject matter of our prior application, Serial No. 179,300, filed July 9, 1917, and entitled Loading machine.

35 Since this digging and conveying mechanism is shown and described with considerable detail in our prior application, and since it is illustrated here simply for convenience and as merely one example of many 40 different mechanisms, which may be used for this purpose, a more or less general description will here suffice. It may be stated, however, that this particular mechanism includes a body 13, which is movably supported on the intermediate base to turn horizontally about an axis which is adjacent the rear end of the intermediate base. It is therefore provided with a front roller 13^a and rear rollers 13^b which engage curved or 45 arc-shaped tracks 12^a and 12^b on the intermediate base and having a common center which is near the rear end thereof. This enables this mechanism to be turned so that the digging or receiving element can be brought up to material located at the sides 55 as well as at the front of the machine without shifting to any extent the rear discharge point. Additionally this digging and conveying mechanism as here shown, includes a 60 reciprocating motor 13^c which is connected at its forward end to the inner member 13^d of a two-part ram carrying pinions 13^e which engage stationary racks 13^f so that when the inner ram member is shifted forwardly and 65 rearwardly it will shift at twice its speed

the outer ram member 13^h, the inner and outer ram members being supported on rollers 13ⁱ and 13^k. The outer ram members 13^h carry castings 13^l and pivoted to these castings are telescopic arms 13^m to the forward ends of which is connected a material receiving and conveying shovel or bucket 13ⁿ. The arms 13^m are provided at their inner or rear ends with gear segments 13° which are concentric with respect to the pivotal axis of the arms, these segments being designed to engage racks 13^p carried by the frame or body 13.

This digging and conveying mechanism is therefore so constructed that when the ram 80 is shifted forwardly, the bucket 13ⁿ is thrust forwardly from the position shown in Fig. 1 and will be filled with material, and when the piston of the motor is retracted, the bucket will be retracted for a distance until 85 the gear segments 13° engage the racks 13^p, whereupon the arms will be rotated about their pivotal axes, swinging the bucket over the machine to, or substantially to the rear end of the intermediate base 12, so that the 90 material will be discharged at the rear of the intermediate base into a suitable mine car or other receptacle to be referred to presently. Then on a forward stroke of the ram, the arms and bucket swing downwardly 95 and forwardly to the position shown in Fig. 1, and then the bucket is thrust forwardly to receive another load.

As the arms swing downwardly to the position shown in Fig. 1, they engage suitable 100 adjustable stops 13^r which are supported by the castings 13^l and as the telescopic arms and bucket are swung upwardly and rearwardly over the machine, the arms are allowed to telescope or shorten so as to enable the machine to be used with very little head room, this being brought about by rollers 13^s, one on the rear end of the forward part of each telescopic arm, these rollers being designed to engage cam surfaces 13^t at 110 the upper edge or periphery of the castings 13^l to which, as before stated, the arms are pivoted.

The material when discharged by the shovel or bucket is preferably received into 115 a mine car 14, which is shown in Fig. 1, this car being designed to run up to the machine along the track rails 11. When the intermediate base is in its rearmost position, that is, when it is not extended beyond the sub-base 10, the car will rest on the tracks 11 just at the rear of the sub-base 10, and as the intermediate base with the digging and conveying mechanism is moved forwardly 120 along or relative to the sub-base, in order that the digging member may be brought into working relationship with respect to the material as the loading proceeds, it is obvious that the mine car must also be fed forwardly or otherwise the material will 130

not be discharged by the bucket into the car. That this may be accomplished, we propose to move the car up onto the sub-base so that the car may always be positioned up 5 close to the rear end of the intermediate base as the latter is advanced. It is for that reason that we provide on the Z-rails 10^e of the sub-base, the inner flanges 10^f which are directly above the main track rails 11, these 10 rails or flanges 10^f being so positioned, and being only slightly above the track rails, that the mine car can be moved up and along these rails 10^f on the sub-base to and even 15 forwardly beyond the position shown in Fig. 1.

It will therefore be apparent that with the improvements which we have provided, the digging and conveying part of the machine can be moved forwardly without the necessity of advancing or laying the track 11 as the digging progresses, that is to say, a section of loosened material of considerable depth can be loaded and the machine can be operated for a long period of time without 25 interrupting its loading operation to lay more track. Of course it will be necessary from time to time to advance the track, but only at infrequent intervals, and in fact, at much less frequent intervals, than with those 30 machines wherein the digging and conveying mechanism can be moved forwardly as the work progresses only in conjunction with the supporting frame, truck or body which rests upon the track rails.

35 While the sub-base here shown is not provided with wheels for advancing the same, it can, nevertheless, be readily advanced, as the work progresses. When all the material within the reach of the machine has 40 been cleaned up, with the intermediate base fully extended, the intermediate base will be retracted, the additional track section will be laid, and then the machine as a whole will be moved forwardly onto the same. If 45 desired, this can be done by placing truck wheels or trucks beneath the sub-base, or the machine may be otherwise advanced. Furthermore, when the intermediate base is fully extended with reference to the sub-base, as shown in Fig. 1, it may be desirable 50 to support the front end of the intermediate base by any suitable supporting device which can be placed under the same, and which may or may not form a part of the machine.

55 It is to be understood that the specific details of the digging and conveying mechanism herein shown, that is to say, the details of the mechanism which is supported on the intermediate base, forms no part of 60 the present invention, and that any other form of digging and conveying mechanism which may be mounted on the intermediate base, and which may be utilized for the purpose of picking up and conveying material 65 rearwardly may be utilized. In this con-

nection it is to be understood that conveying means of radically different form may be utilized, such as a belt conveyor onto which the material can be scraped by a hoe or equivalent device.

Having described our invention, we claim:

1. In a loading machine, a sub-base adapted to rest on a track, an intermediate base supported on the sub-base and movable along the same, said intermediate base being 70 stationary during the normal operation of the machine, a digging and conveying member mounted on the intermediate base and means for giving said member forward filling strokes variable in length.

2. In a loading machine, a sub-base adapted to rest on a track, an intermediate base movably supported on the sub-base and adapted to be projected forwardly beyond the same, said intermediate base being 75 stationary during the normal operation of the machine, and digging and conveying mechanism supported on the intermediate base, and comprising a conveying member adapted to be moved forwardly and rearwardly, and 80 means for giving said member a forward filling movement variable in extent with reference to the intermediate base.

3. In a loading machine, a sub-base having a track, a normally stationary intermediate base supported on the sub-base and movable along the track so that it may be extended forwardly beyond the sub-base as the digging progresses, and material loading 95 mechanism supported on the intermediate base and having means for conveying material from in front of the latter to a rear point, said conveying mechanism including a device adapted to be thrust forwardly to receive a load, and means whereby it may 100 be given forward filling movements of varying lengths.

4. In a loading machine, a sub-base having means by which it may be secured to a track, a normally stationary intermediate 110 base movable lengthwise thereon and adapted to be projected forwardly beyond the same as the loading of material progresses, and conveying mechanism supported on the intermediate base and having means for receiving material from in front of the intermediate base and conveying it to a discharging point, said conveying mechanism including a device adapted to be thrust forwardly 115 to receive a load, and means whereby it may 120 be given forward filling movements of varying lengths.

5. In a loading machine, a normally stationary sub-base, a normally stationary intermediate base movable lengthwise thereon 125 and adapted to be projected forwardly beyond the same as the loading of material progresses, conveying mechanism supported on the intermediate base and having means for receiving material from in front 130

of the intermediate base and conveying it to a discharging point, said conveying mechanism including a device adapted to be thrust forwardly to receive a load, and means whereby it may be given forward filling movements of varying lengths, and means for moving the intermediate base forwardly and rearwardly along the sub-base.

6. In a loading machine, a sub-base, a superstructure movable forwardly along the sub-base and having means for receiving and conveying material rearwardly, said sub-base having means whereby a receiving car may be run up on the sub-base as the superstructure is advanced.

7. In a loading machine, a sub-base, a superstructure having means for receiving and conveying material rearwardly, said superstructure being mounted on the sub-base and

movable forwardly along the same, and said sub-base having a track for a receiving car whereby the latter can be run up on the sub-base close to the superstructure as the latter is advanced.

8. In a loading machine, a normally stationary sub-base, a superstructure mounted on the sub-base and movable forwardly along the same as the loading of material progresses, said superstructure including an intermediate base adapted to travel lengthwise of the sub-base and to be projected forwardly beyond the same, and a laterally swinging material moving element mounted on the intermediate base.

In testimony whereof, we hereunto affix our signatures.

FRANK BILLINGS.

ROBERT P. GREENLEAF.
